UNITED STATES PATENT OFFICE.

LARS G. SCHULT, OF CHICAGO, ILLINOIS.

LOOSE-LEAF BINDER.

SPECIFICATION forming part of Letters Patent No. 679,865, dated August 6, 1901.

Application filed March 11, 1901. Serial No. 50,628. (No model.)

To all whom it may concern:

Be it known that I, LARS G. SCHULT, of Chicago, in the county of Cook and State of Illinois, have invented certain new and useful Improvements in Loose-Leaf Binders, of which the following is a full, clear, and exact description, reference being had to the accompanying drawings, forming a part of this specification, in which corresponding letters ⁵ of reference in the different figures indicate like parts.

The object of my invention is to so construct a binder for loose leaves that one or more leaves may be readily inserted within ¹⁵ said binder or removed therefrom and while therein may be securely retained in place, whether few or many.

To these ends my invention consists in certain special features of construction herein-²⁰ after more particularly described, and definitely pointed out in the claims.

In the drawings, Figure 1 is an edge view of a binder embodying the features of my invention, a portion of the same being broken ²⁵ away. Fig. 2 is an inside view of the clamping-frame. Fig. 3 is a sectional view taken upon the line 3, Fig. 2, viewed in the direction of the arrow there shown. Fig. 4 is a transverse vertical sectional view taken upon ³⁰ the line 4, Fig. 2, viewed in the direction of the arrow there shown. Fig. 5 is a sectional plan view in detail taken upon the line 5, Fig. 3. Fig. 6 is a transverse vertical sectional view taken upon the line 6, Fig. 2, viewed in the direction of the arrow there shown; and Fig. 7 is a plan view in detail of ³⁵ the lock-controlling gears.

Referring to the drawings, *a b* respectively represent two metal binding-plates, which are ⁴⁰ arranged parallel to each other and form the main or primary feature of the framework of my improved binder. Rigidly attached to the plate *a* is a sheet-metal expansion-plate *c*, which is provided with a flange *d*, formed ⁴⁵ at right angles to the main body of said plate, which flange is attached to the plate *a* by means of screws *e*. A similar plate *f* is attached in like manner to the plate *b* by means of the flange *g*. The plates *c f* form the ex- ⁵⁰ pansion back of the binder and are arranged in contact with and adapted to slide upon each other. Each of said plates is shaped at the respective ends in the form of a scroll, as

shown at *h h* and *i i*, respectively, the latter being of a diameter adapted to fit closely ⁵⁵ upon and inclose the former. This feature enables the former to slide within the latter to permit the expansion of the back, while retaining said parts in alinement and preserving the back-plates *c f* in parallel planes. ⁶⁰ In order to render said end scrolls rigid with the plates *a b*, I form flanges *k k* upon the scrolls *h h* and like flanges *l l* upon the scrolls *i i*, the former of which flanges are attached by means of screws, as shown, to the plate *a* ⁶⁵ and the latter in like manner to the plate *b*. Said scrolls form telescoping tubes, within each of which is inserted a spiral compression-spring *j*, the ends of which bear upon the plates *a* and *b*, as clearly shown in Fig. 6, ⁷⁰ and tend to force the two apart, as hereinafter described.

Rigidly attached to the plate *a* are wire studs or posts *m n*, which are in alinement with similar posts *m' n'*, attached in like manner to the plate *b*. The posts *m* are longer than the posts *m'* and are pointed, as indicated, the points being fitted to engage with corresponding depressions in the short posts, while the posts *n'* are long and are fitted to ⁸⁰ engage in like manner with the short posts *n*. The several posts are adapted to pass through perforations in the leaves *o*, Fig. 1, and to retain the latter in place, the object in attaching said long and short posts alternately to ⁸⁵ opposite plates being to retain the leaves in contact with at least two of the posts when the binder is unlocked and expanded, as hereinafter set forth.

In order to accommodate my improved ⁹⁰ binder to varying numbers of leaves, I provide the following-described adjustable locking mechanism: Rigidly attached to the plate *b*, midway between the ends of the latter, by means of a flange *p* and screws *q*, Figs. 2, 3, ⁹⁵ 4 and 5, is a flattened sheet-metal tube *r* of a length corresponding to the width of one of the back-plates and having one end thereof open. The rear of said tube is placed next to the back-plate *c*. Located within said tube ¹⁰⁰ and pivoted at *s*, Fig. 5, near the open end thereof, is a pawl *t* in engagement with a retaining-spring *u*, secured within said tube, as shown in said last-named figure. A top view of said pawl is also shown in Fig. 3. Swiv- ¹⁰⁵ ed in the plate *a* is a rack-bar *v*, having

- teeth v' , to the outer end of which bar is rigidly attached a segmental pinion w , the rotation of which is limited by means of stop-pins w' . A gear-wheel x is mounted upon the plate a by means of a pin or screw y and adapted to engage and actuate the pinion w . Bores or depressions z are provided to enable said gear to be rotated by means of a special key having prongs shaped to fit said depressions.
- 10 The rack-bar v is covered by means of a sheet-metal shield v^2 , having a flange v^3 attached by means of screws v^4 to the plate a , said shield being so shaped as to cover and telescope with the flat tube r , into which latter
- 15 the rack-bar v enters in such a manner that the pawl t may be free to engage the teeth of said rack-bar when the latter is rotated to an operative position, as hereinabove stated.
- A sheet-metal plate c' , Figs. 2 and 3, is loosely connected by means of a pin c^2 to the back-plate c , a slot c^3 being formed in said plate, in which said pin is free to move to provide for the necessary expansion of the binding-plates. One end of said plate c' is connected with the back-plate f by means of a pin c^4 , secured within a suitable opening, thereby enabling said plate c' to limit the expansive movement of the back-plates when the locking mechanism is released. Upon disconnecting the pin c^4 the sliding sections of the back may be entirely separated. The usual covers o' , Fig. 1, binged in the ordinary way at o^2 , are attached by means of said hinge portions to studs o^3 , which are in turn screwed or otherwise rigidly secured to the plates a b , respectively.
- The operation of my improved device is as follows: Assuming the two parts of the adjustable back to be separated, the springs j are placed within the tubes formed by the scrolls h h . Said scrolls are then inserted within the scrolls i i , while the tube r is caused to telescope with the part v^2 and the rack-bar to enter said tube. If the rack-bar is adjusted in the position shown in Fig. 5, the pawl t will engage with the teeth of said rack and retain the connected parts in position against the expansive action of the springs j . The pin or stud c^4 of the plate c' is then connected with the back f , which serves to limit the expansive movement of the two sections when the pawl is disconnected from the rack. The two sections may be readily drawn together by compression to any desired degree, in which position they are held by the engagement of the pawl and rack. When it is desired to release the pawl and rack from engagement, a key is inserted in the holes z of the gear x , and the latter is turned until the pinion w engages one of the stops provided therefor. This causes a sufficient rotation of the rack-bar v to turn the teeth away from and to cause the smooth portion thereof to be brought into contact with the pawl t . The springs j then cause the back-sections to expand, as indicated in dotted lines in Fig. 2, until limited by the plate c' . When so expanded, the leaves, which are perforated to

receive the retaining-posts, are placed in position and the sections compressed until the plates a b are brought into contact with the leaves, as indicated in Fig. 1, where, assuming the rack to be set in a locking position, they are securely retained.

By reason of the telescoping features described my improved binder is rendered light, simple, and compact and may be cheaply constructed and easily manipulated. A further advantage is that a powerful compression is not necessary in order to retain the leaves in place, they being secured and always retained with their edges even by the retaining-posts. Moreover, it is obvious that the device may be used with a single leaf and from that up to the full capacity of the binder.

The locking device is simple and durable and it cannot become disconnected except through the action of the key.

Having thus described my invention, I claim—

1. A device of the class described, in which are combined parallel binding-plates, overlapping back expansion-plates arranged at right angles thereto, the same being shaped in scroll or tubular form at the respective ends to telescope with each other, and an adjustable locking mechanism for securing the binding-plates in position when compressed upon the leaves, substantially as described.

2. The combination in a device of the class described, of parallel binding-plates, back-plates arranged at right angles thereto, one of said back-plates being rigidly secured to one and the other to the other of said binding-plates, said back-plates being shaped at the respective ends to form interlocking telescoping tubular scrolls, expansion-springs arranged within said tubular scrolls, and an adjustable locking mechanism for locking said plates together, substantially as described.

3. The combination of parallel binding-plates, back-plates arranged at right angles thereto, one of said back-plates being rigidly attached to one and the other to the other of said binding-plates, said back-plates being shaped at the respective ends to form interlocking telescoping tubular scrolls, expansion-springs within said tubular scrolls, an adjustable locking mechanism, and a series of leaf-retaining posts, each post consisting of one long and one short member of like diameter, one being pointed and the other recessed to receive the point thereof, said members being alternately attached to opposite binding-plates, whereby, in adjacent posts, a short member may stand adjacent to a long one, substantially as described.

In testimony whereof I have signed this specification, in the presence of two subscribing witnesses, this 9th day of March, 1901.

LARS G. SCHULT.
